T. E. ANDERBERG.
AUTOMATIC DRAFT REGULATOR,
APPLICATION FILED DEC. 27, 1918.

1,307,950.

Patented June 24, 1919.

UNITED STATES PATENT OFFICE.

THOMAS E. ANDERBERG, OF SANDY, UTAH, ASSIGNOR OF ONE-THIRD TO WALTER W. MOORE AND ONE-THIRD TO ALBERT L. ANDERBERG, BOTH OF SALT LAKE CITY, UTAH.

AUTOMATIC DRAFT-REGULATOR.

1,307,950.

Specification of Letters Patent. Patented June 24, 1919.

Application filed December 27, 1918. Serial No. 268,559.

To all whom it may concern:

Be it known that I, THOMAS E. ANDERBERG, a citizen of the United States, residing at Sandy, in the county of Salt Lake and 5 State of Utah, have invented certain new and useful Improvements in Automatic Draft-Regulators; and I do declare the following to be a full, clear, and exact description of the invention, such as will enable 10 others skilled in the art to which it appertains to make and use the same.

My invention has for its object to provide an extremely simple and inexpensive yet highly efficient and desirable device 15 which will automatically regulate the burning of the fire in a stove or the like, provision being made whereby the increased draft when the fire is burning violently will open the damper to admit fresh air into the 20 smoke pipe, thus checking the draft and similarly checking the fire.

With the foregoing in view, the invention resides in the novel features of construction hereinafter fully described and claimed, reference being made to the accompanying drawing which forms a part of this application.

Figure 1 is a front elevation of the invention applied to a smoke pipe.

30 Fig. 2 is a side elevation.

Fig. 3 is a vertical section on the plane indicated by the line 3—3 of Fig. 1.

Fig. 4 is a detail elevation of the damper plate and its rock shaft.

35 Fig. 5 is a small side elevation illustrating the manner in which the device may be applied to a stove rather than to the smoke pipe.

In the drawing above briefly described the 40 numeral 1 designates a vertically disposed plate which is curved in horizontal section to conform with the shape of the pipe P or stove S upon which it is to be employed, it being intended that this plate shall be secured either to the pipe as seen in Figs. 1, 2 and 3, or directly to the stove as depicted in Fig. 5. Any suitable means, such as stove bolts 2, may be employed for attaching the plate 1 and since the plate in question will in 45 most cases be of cast metal, only a few fasteners are required.

An opening 3 is formed in plate 1 for registration with a similar opening in the stove or pipe, and an arched cowl 4 is

joined integrally to said plate and inclines 55 downwardly and outwardly from the upper end and sides of the opening 3, said cowl having an open lower end 5 which inclines downwardly to the lower end wall 6 of the opening 3. The portion 7 of plate 1, directly beneath opening 3, inclines upwardly and inwardly and is straight along its upper edge to form the aforesaid wall 6; and a rock shaft 8 is mounted parallel with and in close relation to said wall, suitable bearings 9 being shown secured to the plate 1 for supporting said shaft, although other appropriate provision could well be made.

The shaft 8 is by preference formed of a single wire rod bowed between its ends to 70 provide an upstanding projection 10, this projection contacting with the outer side of a sheet metal damper plate 11 which is located within and normally closes the open end of the cowl 4, said end being provided with 75 an integral, inwardly extending flange 12 against which the plate 11 normally seats. The plate 11 is provided with a central tongue 13 and with knuckles 14 on opposite sides thereof, said knuckles being clenched around 80 the shaft 8 on opposite sides of the extension 10, while the tongue 13 is bent into angular relation with the plate to abut the inclined portion 7 of the plate 1, so as to form a stop for limiting the inward or opening movement of said plate. By the provision of the 85 knuckles 14 on opposite sides of the projection 10, the damper plate 11 may be rigidly secured to the shaft 8 and by the same stamping operation which forms said knuckles, the 90 tongue 13 is provided. These features thus assist in producing an extremely simple and inexpensive device. It may also be considered that in order to provide a straight wall 95 6 for the opening 3, it is necessary that the 95 part 7 of the plate shall incline and it is highly advantageous to employ this inclined part in connection with the tongue 13, to limit the opening of the damper.

Any preferred provision may be made for 100 normally closing the damper, but in most instances one end of the shaft 8 will be bent downwardly to provide a crank arm 15 upon which a suitable weight 16 is threaded or adjustably mounted in any other suitable 105 manner. By properly adjusting the weight the damper may be made to open automatically when the fire is burning as required

Until the fire has reached a predetermined intensity, the damper will remain closed, but when this occurs, the draft is sufficiently strong to overcome the action of the weight 5 16, thus permitting the damper to open and admit fresh air to check the fire.

From the foregoing, it will be seen that my invention is of extremely simple and inexpensive nature, yet that it will be highly 10 efficient and desirable. Since probably the best results are obtained from the details shown and described, they may well be followed, but within the scope of the invention 15 as claimed, numerous minor changes in size, proportion and other minor details may well be made.

What I claim is:

1. In an automatic draft regulator, a plate having means for securing it to a stove pipe 20 and provided with an opening, an arched cowl inclining downwardly and outwardly from the upper end and sides of said opening, said cowl having an open lower end inclining downwardly to said plate and terminating at the lower end of said opening, 25

the portion of the plate directly below said opening inclining upwardly and inwardly and forming the lower end wall of said opening, a flange extending inwardly from said open lower end of said arched cowl, a 30 damper within said cowl and normally contacting with the inner side of said flange, a rock shaft parallel with said lower end of the aforesaid opening and carrying said damper, a weight on said shaft for controlling the opening of said damper, and a projecting stop on said damper adapted to strike said inclined part of said plate to limit the opening movement of said damper. 35

2. A structure as specified in claim 1; 40 said rock shaft having an upstanding projection; said damper being stamped from sheet metal and having two knuckles and a tongue; said knuckles being clenched around said shaft on opposite sides of said projection and said tongue being bent into angular relation with said damper to form said stop. 45

In testimony whereof I have hereunto set my hand.

THOMAS E. ANDERBERG.
